UNITED STATES PATENT OFFICE.

WILLIAM B. ARNOLD, OF NORTH ABINGTON, MASSACHUSETTS.

MACHINE FOR SCOURING HEELS.

SPECIFICATION forming part of Letters Patent No. 732,814, dated July 7, 1903.

Application filed April 11, 1901. Serial No. 55,361. (No model.)

To all whom it may concern:

Be it known that I, WILLIAM B. ARNOLD, a citizen of the United States, residing at North Abington, county of Plymouth, State of Massachusetts, have invented an Improvement in Machines for Scouring Heels, of which the following description, in connection with the accompanying drawings, is a specification, like letters on the drawings representing like parts.

Considerable expense, time, and labor are at present consumed in the necessary operation of preparing leather heels for the finishing operation, this being usually done by scouring them on sandpaper buffing-wheels.

My invention comprises in its general embodiment a series of flexible abrading-disks of sandpaper of large area, which, although individually very flexible and frail, are used in considerable numbers superimposed directly upon each other and secured at their center only, being entirely unrestrained at all other points and free to stand more or less apart excepting at the center.

One object of my invention is to prevent as far as possible the rapid wearing out or tearing of the sandpaper, or, in other words, to lengthen its life and efficiency while obtaining a quick and rapid abrading-surface,

and I have found that by employing a number of sheets of sandpaper mounted as above explained on a shaft at one side or supporting-face of a back or disk the active sheet will stand out firmly and strongly with much less

liability to tear than if used singly, so that when a top lift of a heel is pressed against the same the nails or the like therein may be pressed firmly against the face of the sandpaper without materially disturbing its path

of rotation and without tearing it, the sandpaper at the point of pressure yielding inwardly slightly, but resuming at once its circular path of rotation upon passing the nail or other article pressed against it, the body

of slightly-separated and rapidly-revolving sheets of sandpaper before mentioned providing a resilient cushion and permitting the abrading-sheet to yield under the pressure of the work and yet supporting the same and reinforcing the natural tendency of the sandpaper to maintain its path of rotation, whereas when used alone a single sheet of sandpaper would

be disturbed in its rotative movement and actually torn or destroyed under the same pressure.

The constructional details and further advantages of my invention will be pointed out in the course of the following description, reference being had to the accompanying drawings, illustrative of one form of my invention, and the latter will be more particularly defined in the appended claims, also forming a part of this specification.

In the drawings, Figure 1 shows my invention in front elevation. Fig. 2 is a vertical sectional view thereof, taken on the line 2 2, Fig. 1. Fig. 3 is a horizontal sectional view taken on the line 3, Fig. 2.

It will be understood that my invention may be mounted and operated by any convenient means, being herein shown as mounted on a stand *a*, having a bearing *a'* at its upper end in which is journaled a shaft *b*, driven by a high-speed pulley *b'*, secured thereto at one side of the bearing, while at the other side of the bearing is a disk *c*, having a shoulder or flange *c'* for holding an operating member *c''* of the clamping device. On the face of the disk *c* is preferably mounted a felt pad *c''*, and in front of this are the sheets of sandpaper *c'''*, it being usual to secure a large number of sheets in place at the start and remove them one by one as they become worn.

It is not new to use sandpaper for scouring heels; but as heretofore used in rotary scourers it has been used a single sheet at a time, being pressed directly on the smooth and usually hard carrying-surface, so that when in use the heel, and especially the nails thereof, have been shoved against the sandpaper, the latter has worn away rapidly, and accordingly various inventions have been made in special cushion-like backings. I have found, however, that I can get all the cushion required and can produce a yielding and yet durable and permanent abrading-surface simply by securing a plurality of sheets at their center to a high-speed disk. The high speed of rotation of the wheel or disk will maintain the sheets of sandpaper perfectly flat and sufficiently stiff to endure the heavy pressure brought upon them in scouring heels and shoe-bottoms, the several sheets of sandpaper being free and unrestrained excepting

at their center, whereby they may separate sufficiently to give a superior cushioning effect, permitting the sandpaper surface to conform instantly to the changing surface of the 5 heels while scouring the leather and nails thereof down smooth and even. Not only is the scouring effect rendered extremely sensitive and rapid, thereby permitting a large number of heels to be done in a given length 10 of time, but the life of the sandpaper is increased, as it does not wear away so rapidly when it can give slightly. When a sheet becomes smooth, the operator simply catches the sheet at its edge and tears it off instantly, 15 without any manipulation of the clamp, and if a ragged edge should project slightly from the center it is of little importance, as the area at the center is necessarily small.

Any kind of suitable clamp may be employed; but I prefer to use the form herein shown, which consists of a washer or circular clamping-plate c^5 , having a hole c^6 at one side of the center to fit over the securing button or head c^7 of the clamping-bolt, and a neck 25 c^8 to slip down over the neck c^9 of said bolt behind said head, as will be clearly understood viewing Fig. 1 in connection with Fig. 2. The bolt is provided with an elongated opening c^{10} , in which an eccentric hub c^{12} 30 from the operating member c^2 rests, there being preferably a spring c^{13} clamped behind the clamping-bolt in a recess provided axially of the shaft b for normally maintaining the bolt under a tendency to move outwardly to the dotted-line position, Fig. 3.

I am aware that it is not new to provide a central clamp for clamping a plurality of parts together, and I am also aware that this has been done in buffing-wheels in which the 40 peripheral edge of the wheel constitutes the buffing-surface, said wheels being made of such material as sheets of leather and cloth, and therefore I wish it clearly understood that I do not in any sense intend to claim such 45 construction; but rather my invention resides in the discovery that by employing a central clamp for a plurality of disk-face scouring-sheets for shoe bottoms and heels and leaving

the sheets of sandpaper free at their edges an exceedingly effective scouring-surface results. 50

The abrading-surface of my device is in use exceedingly mobile and quick or active, so that it responds readily in any direction to pressure and instantly recovers itself when 55 released. This is the new result, upon which my invention is founded, and it also enables me to utilize more economically the sandpaper, renew the scouring-surface more quickly, 60 scour the shoes very rapidly and perfectly, and get new results generally.

Having described my invention, what I claim as new, and desire to secure by Letters Patent, is—

1. A machine for scouring heels and shoe-bottoms, comprising a stand, a shaft, a disk mounted on said shaft, a plurality of sheets of sandpaper secured on one face of said disk, a single clamping device for said sheets, said clamping device being located at the center 70 of said disk, and the sheets extending without constraint from said clamping device to their extreme peripheral edges, and means for rotating said disk and sheets at high speed. 65

2. A machine for scouring heels and shoe-bottoms, comprising a stand, a shaft, a disk mounted on said shaft, a plurality of sheets of sandpaper secured on one face of said disk, a single clamping device for said sheets, said clamping device being located at the center 80 of said disk, and the sheets extending without constraint from said clamping device to their extreme peripheral edges, and means for rotating said disk and sheets at high speed, 75 said clamping device consisting of a bolt held axially in the end of said shaft, and provided with a quick-acting operating member for moving it in and out, and at its outer end having a removable washer or clamping-plate. 85

In testimony whereof I have signed my 90 name to this specification in the presence of two subscribing witnesses.

WILLIAM B. ARNOLD.
